United States Patent Office

Des. 188,419

Patented July 19, 1960

188,419

CORD CONNECTOR

Paul P. Danesi, Attleboro Falls, Mass., assignor to Royal Electric Corporation, Pawtucket, R.I., a corporation of Delaware

Filed July 22, 1959, Ser. No. 56,887

Term of patent 14 years

(Cl. D26—1)

FIG. 1

FIG. 2

FIG. 3

FIG. 4

Fig. 1 is a perspective view of a cord connector, showing my new design;

Fig. 2 is a top plan view;

Fig. 3 is a side elevational view, the opposite side being substantially a mirror image thereof; and

Fig. 4 is an end elevational view thereof.

The dominant features of my new design are shown in solid lines in the drawing.

I claim:

The ornamental design for a cord connector, as shown and described.
